Filed Jan. 15, 1960, Ser. No. 59,064

Term of patent 14 years

(Cl. D91—3)

FIG. 1.

FIG. 2.

FIG. 3.

FIG. 4.

The rear end of the faucet fitting is substantially plain.

The dominant features of my design reside in the portion shown in full lines.

I claim:

The ornamental design for a faucet fitting, as shown and described.
